UNITED STATES PATENT OFFICE.

MERRITT GREENE, OF MARSHALLTOWN, IOWA.

WIRE-BARB.

SPECIFICATION forming part of Letters Patent No. 380,884, dated April 10, 1888.

Application filed October 26, 1887. Serial No. 253,393. (No model.)

To all whom it may concern:

Be it known that I, MERRITT GREENE, a citizen of the United States, residing at Marshalltown, in the county of Marshall and State of Iowa, have invented certain new and useful Improvements in Wire-Barbs, of which the following is a specification.

The object of my invention is to provide a wire-barb whose ends terminate in needle-points, and whose central portion is flattened on one side for a sufficient distance to wrap entirely around the strand and form a shoulder which shall keep the barb always at right angles to the strand, and which constitutes a socket with sufficient bearing to prevent the barb from turning.

It is desirable in forming wire-barbs to economize material as much as possible, and if the proper rigidity and firmness of the barb are secured I have found that barb to be the best for practical purposes which wastes the smallest amount of material in wrapping around the strand or strands of the fence which must support the barb. I have found, therefore, that a barb which is wrapped around only one strand is much preferable to one which is wrapped around both strands of the fence, if only the former can be rendered sufficiently stiff to resist the onslaught of cattle. Some wire-barb manufacturers have thought it an improvement in barbs to make them somewhat yielding; but I have found that a reasonably stiff barb is preferable.

I am aware that comparatively short barbs have been employed by giving a sort of bend to the center of the barb, so that it passes between the strands of the fence, and flattening both sides of the barb, so that it is held by the bends of the barb; but I do not find such barbs possessing the usefulness and firmness requisite for use on barb-wire fences, as the barb is much weakened by this double flattening; and I have made my barb, therefore, to form a complete turn around one of the strands, so that it cannot be detached therefrom without cutting or unwinding.

I am also aware that round or unflattened barbs have been made to form a complete turn on one of the strands by bending the barb

sharply back to form a shoulder above and below the strand; but I do not find that such barbs have the requisite usefulness and firmness, and I have therefore flattened the inner side of the center of my barbs to avoid the bending back and to secure a firmer hold on the strand.

One form of the barb by which I accomplish the above desirable results is shown in the accompanying figures, in which—

Figure 1 represents the barb as applied to the fence. Fig. 2 represents the barb before twisting. Fig. 3 shows the shape the barb takes when twisted on the strand, the strand itself not being shown.

Same letters indicate similar parts in the different figures.

A B are the two strands which twisted together form the cable of the fence.

C is a barb. This barb is made out of a piece of cylindrical wire of desired diameter, and is formed by flattening one side of the central portion, as shown at a, for approximately the exact distance required to wrap around one of the strands A or B, and forming sockets or shoulders which enable them to grasp the strand very closely and firmly. The two ends of the barb-wire are then sharpened, as shown at b, into what are known as "needle-points," and these points stand away from the wire ready to receive and stop the force of cattle rushing against the fence.

The many advantages and desirable features of my improved barb are, I think, sufficiently obvious without further explanation.

I claim—

A wire-barb whose ends terminate in needle-points and whose central portion is flattened on one side for a sufficient distance to wrap entirely around the strand and form a shoulder which shall keep the barb always at right angles to the strand, and which constitutes a socket with sufficient bearing to prevent the barb from turning.

85

MERRITT GREENE.
